UNITED STATES PATENT OFFICE.

GEORGE A. EDE, OF COBDEN, ILLINOIS.

STAPLING MACHINE.

1,411,007.

Specification of Letters Patent. Patented Mar. 28, 1922.

Application filed August 11, 1921. Serial No. 491,375.

To all whom it may concern:

Be it known that I, GEORGE A. EDE, a citizen of the United States of America, and a resident of Cobden, in the county of Union and State of Illinois, have invented certain new and useful Improvements in Stapling Machines, of which the following is a full, clear, and exact description, reference being had to the accompanying drawing, forming a part of this specification.

This invention relates to improvements in stapling machines and particularly to the class of stapling machines used for forming and driving staples, in the manufacture of veneer baskets.

More specifically stated, an object is to produce a stapling machine which includes a means for positively returning the staple-forming and driving members after each staple-forming and driving operation whereby the entire dependency for the return of said staple-forming and driving members upon unreliable springs is avoided.

A further object is to provide a means whereby the wearing parts of the retracting means may be renewed without the necessity of changing the larger and more expensive associated parts.

With the foregoing and other objects in view, the invention comprises the novel construction, combination and arrangement of parts hereinafter more specifically described and illustrated in the accompanying drawings wherein is shown the preferred embodiment of the invention. However, it is to be understood that the invention comprehends changes, variations and modifications which come within the scope of the claims hereunto appended.

Fig. I is a plan of my improved stapling machine.

Fig. II is a section on line II—II of Fig. III with the spring housing removed.

Fig. III is a longitudinal section through the machine.

Fig. IV is a transverse section on line IV—IV of Fig. I, part of the form-post being broken away.

Fig. V is an enlarged fragmentary section showing one of the rollers for returning the

staple-forming and driving members after the staple-forming and driving operation, together with its supporting plate and a fragment of one of the disks.

Fig. VI is a fragmentary section of the parts shown in Fig. V showing the manner of securing the roller supporting plates to the disk.

Fig. VII is a perspective view of the roller-supporting plate shown in Figs. V and VI, showing the rollers and dowels secured thereto.

Fig. VIII is a horizontal section through the staple forming mechanism showing the slideable fingers together with the cams for operating same.

Fig. IX is an inverted plan of part of the mechanism shown in Fig. VIII.

Fig. X is an enlarged section showing the mechanism for forming and driving the staples.

Fig. XI is a perspective view of one of the staple-forming fingers.

Fig. XII is a perspective view of one of the staple-cutting and driving devices.

Fig. XIII is an enlarged detail of the wire feeding mechanism.

Fig. XIV is a perspective of one of the slides by which the staple-form fingers are retracted after the staple has been formed.

Fig. XV is a section on line XV—XV of Fig. XII.

In the drawings 1 designates the frame of the machine upon the rear portion of which are mounted bearing boxes 2 in which the main shaft 3 is mounted. This shaft is provided with a crank 4 at each side of which is a cam member 5 provided with cam faces 6 and 7 (Figs. I and II). 8 designates a reciprocating rod having its rear end journaled to the crank 4 of the main shaft 3 (Fig. III) and having its forward end reduced into a stem 9 at the end of which is a nut 10, that confines an expansion spring 11. The stem 9 of the reciprocating rod 8 is loosely positioned in the leg 12 of a reciprocating carrier 13, which rides upon guides 14 of the table 1^a of the machine frame and is confined by bars 15 (Fig. IV). The leg 12 of the carrier 13 is held normally projected

100

in a rearward direction by the spring 11 on the stem 9. The carrier 13 is provided with a longitudinal slot 16 (Figs. II and III).

17 is a post bearing a washer 18 on its lower portion and having its lower end extending through the longitudinal slot 16 in the carrier 13. The lower termination of the post is threaded as seen at 19 (Figs. III and IV) and is adapted to receive a nut 20 whereby said post 17 may be clamped at any point in the slot 16. The post 17 is adapted to support a basket-form 21, that is rotatably mounted thereon and adapted to receive the basket to be stapled and permit of each of its sides being moved into a position facing the stapling mechanism.

22 designates standards mounted upon the frame of the machine by which the staple wire delivery and feed mechanism is supported. The staple wires A (Figs. III, VIII and X) are arranged preferably on reels (not shown) which may be supported by arms 23 extending from the rear portion of the machine frame. There are two of 25 said arms and reels from each of which a wire is conducted to one of the guide tubes 24, mounted upon arms 25 supported by the standards 22. The wires on passing through said tubes are directed downwardly as seen 30 in Fig. III.

26 designates a feed wheel shaft journaled in the standards 22 and bearing wire-feeding wheels 27, that are located beneath the exit ends of the wire-guide tubes 24. 35 The feed wheels 27 are opposed by rollers 28 mounted upon rods 29, loosely positioned in standard arms 22'. The feed wheel shaft is rotated through the medium of a ratchet wheel 30 fixed thereto and a rocker arm 31, 40 that carries a spring-controlled pawl 32 for engagement with said ratchet wheel. The rocker arm 31 is loosely mounted on the feed wheel shaft and is united to the main shaft 3 of the machine by a connecting rod 33 fitted 45 to a crank disk 34 carried by said main shaft.

35 designates a cross-bar extending transversely of the machine immediately beneath the delivery and feed mechanism and in which are seated vertical wire guide tubes 36 into 50 which the wires A enter as they are fed downwardly from the feed wheels 27. The guide tubes 36 lead to vertical channels 37 extending through the cross bar 35 (Figs. III, VIII and IX). The cross bar 35 is 55 mounted upon a table 38 (Fig. III), that is surmounted by outer guides 39, and a central portion 41 located in the rear of the cross bar 35 (Fig. II). 42 in a cap plate (Fig. I) mounted on said guides and partition.

60 43 designates staple-forming bars positioned on the table 38 between the guides 39 and the central portion 41 for reciprocation, each bar 43 being provided at its rear end with an upstanding portion 44 having a cam

groove 45 (Figs. III and XII), the utility 65 of which will be hereinafter pointed out. A pair of forming fingers 46 is rigidly secured to each forming bar 43 and the ends of these fingers are provided with wire cutting edges. 70

47 designates driving bars positioned alongside of the staple forming bars 43 and provided with drive fingers 48 positioned intermediate of the forming fingers 46, between which they operate, as seen most 75 clearly in Figs. X and XII. The slide bars 43 and 47 are united to each other by tongue and groove connection, as illustrated in Fig. XV.

49 designates staple-form fingers (Figs. 80 VIII, IX and X) reciprocally positioned longitudinally of the cross bar 35 and adapted for movement across the channels 37 as seen in Fig. VIII. These fingers are normally projected across said channels by 85 springs 50 located at the rear of the fingers. The form fingers 49 are provided with cams 51 having beveled faces 52 (Figs. VIII, IX and XI).

53 designates retracting slides for withdrawing the form fingers 49 against the action of the springs 50. These retracting slides are positioned against the guides 39. Each of the slides 53 (Figs. II, XII and XIV) is provided with a leg 54 that enters a 95 notch 43' in the forming bar 43.

55 designates a pair of disks which are mounted on the main shaft 3 of the machine and are preferably formed integral with the cam members 5, each of said disks being provided with a pair of apertures 56. Located on each of said disks adjacent to said apertures is a plate 57 (Figs. III, V and VI and VII) which supports pins 58 on each of which is mounted a roller 59, said rollers 59 being adapted to extend through the apertures 56 in the disk 55. Supported by each plate 57 is a pair of dowels 60 adapted to extend into recesses in the disk 55. A screw 62 (Figs. V and VI), adapted to pass 105 through a central opening 63 in the plate 57 and screw into the disk 55, secures said plate 57 in place.

It will be apparent that in the event of the rollers 59 becoming worn from continued use, the plate 57 and rollers 59 may be removed by the removal of a single screw, that indicated by the reference character 62, and that because of the use of dowels 60 the plate 57 is very securely fastened in place 115 without any danger of same being displaced.

64 designates return bolts (Figs. I and III) slidably mounted in housings 65 forming parts of the cap plate 42. These bolts 64 are located above the staple-forming and 120 driving bars and their rear ends project from said housings 65 toward the upstanding portions 44 of the staple forming bars 43. Each

of these return-bolts is backed by an expansion spring 66 that holds the bolt normally projected in a rearward direction to bear against the upstanding portions 44 as seen in Fig. III.

67 designates dies (Figs. I, II, III and X) mounted in uprights 68 on the carrier 13 in positions to place said dies directly in advance of the channels 37 in the cross bar 35, so that when the parts of the stapling mechanism are moved, the dies and the forming fingers 46 and the driving-finger 48 will approach each other, as suggested by Fig. X.

In the practical use of this machine, assuming that the stock from which the basket is to be produced has been placed over the basket form 21 (Figs. I and III) in a folded condition, so that the rim of the basket will lie at the rear of the dies 67 when the form is rotated on its post. The main shaft 3 is then set in motion and the first action thereof is to move the rod 8 in a rearward direction from the position in which it is seen in Fig. III. On the movement of said rod, the carrier 13 is moved rearwardly toward the cross bar 35. Continued rotation of the main shaft carries the cam members 5 in the direction of the arrow in Fig. III. The cam face 6 of each cam member 5 comes into contact with the rear end of a forming bar 43, moving the fingers 46 of said bars into the channels 37 of the cross-bar 35, and the forward cutting edges of said fingers act to sever sections of the stapling-wire A 35 which projects downwardly into said channels in the rear of the form-fingers 49 which are normally projected across said channels. Continued movement of the forming fingers 46 results in the formation of a staple, which is produced on the form bar 49 between the forming fingers 46 as seen in Fig. X. As soon as the staples have been produced the movement of the forming slide bars results in the retracting slides 53 engaging the beveled faces 52 of the cams 51 on the form fingers 49. When the retracting slides 53 engage said cams 51 the form-fingers 49 are retracted out of the channels 37, thereby moving them to positions entirely beyond the staples. The driver fingers 48 (Fig. X) of the driven bars 47 are then carried forward under the action of the cams 7 and said driver fingers 48 push the previously formed staples forwardly from their positions between the forming fingers 46 and force them through the basket on the basket form 21 and their ends are clenched by coming in contact with the dies 67, which were previously moved rearwardly to the position shown in Fig. X.

A complete rotation of the main shaft will form and drive a pair of staples, and will return the basket form 21 to its forward position, and because of the spring-pressed re-

turn bolts 64 exerting a rearward pressure 65 against the upstanding portions 44 of the staple-forming bars 43 (Fig. III) said staple-forming bars 43 will be forced against the cam members 5, and as the extended portions of said cam members 5 rotate away 70 from the rear ends of said staple forming bars these bars will be moved rearwardly by the action of said spring-pressed bolts 64.

To insure the return movement of the staple-forming bars 43 even though the springs 66 should fail to function properly, I provide each of the staple-forming bars 43 with a cam groove 45 (Figs. III and XI) which is located adjacent to the rear end of said staple-forming bar. The disks 55 80 are each provided, as has been explained, with a pair of projecting rollers 59. Assuming now that the springs 66 fail to function properly the rotating disks 55 will carry their projecting rollers around and said rollers will enter the cam slots 45 in the staple forming bars 43 and because of the inclined faces 45' in said slots with which said projecting rollers successively contact, said staple forming bars will be positively 90 returned to their rearward positions.

The staple-forming bars 43 and the driver bars 47 are arranged to move independently under the actuation of the cams that strike them to move them forward; but inasmuch 95 as only the staple-forming bars are engaged by the return bolts 64 and the projecting rollers 59 to move them rearwardly after they have been actuated in a forward direction, it is necessary to provide connection between the bars for the return of the driver bars. This connection I provide by the application of pins 69 to the forming bars, which project into longitudinal slots in the driver-bars and which engage the driver-bars 100 in said slots, as seen in Fig. III to unite said bars 43 and 47, so that they will travel together on their return stroke.

Under ordinary conditions the spring-pressed bolts 64 (Figs. I and III) will retain 110 the staple-forming bars 43 in engagement with the rotary cams 6, so the spring-pressed bolts will ordinarily restore said bars 43 after the staple-forming operations. This is a desirable restoring means, for the 115 springs noiselessly perform their functions without causing destructive hammer blows in the restoring means. However, actual experience has shown that a crooked piece of wire, or an improperly formed staple will 120 occasionally be caught in the machine so as to retard the fingers 46 and 48, and in this event the spring-pressed bolts 64 will not restore the staple-forming and driving bars. It is, therefore, an advantage to combine 125 with the yielding restoring means, a positive restoring means whereby the forming and driving bars are positively restored when

the springs fail to perform their functions. This positive restoring means includes the rollers 59 which normally pass idly through the cam grooves 45 in the rear ends of bars 43 without transmitting motion to said bars 43, but when a restoring spring 66 fails to restore its bar 43, the rollers 59 associated with said bar will enter the cam groove 45 and engage its inclined wall 45', so as to positively restore the bar 43. The slot and pin connection at 69 in Fig. III will cause the staple-driving bar 47 to return with the forming bar 43.

I claim:

15. 1. A stapling machine comprising staple-forming mechanism, a staple-driving bar cooperating with said staple-forming mechanism, means whereby said staple-driving bar is moved to drive a staple, a spring tending to return said bar, and means whereby said staple-driving bar is positively returned after such staple-driving operation.

20 2. A stapling machine comprising staple-forming mechanism including a staple-forming bar, a staple-driving bar cooperating with said staple-forming bar, a revolute shaft, a cam mounted on said revolute shaft to engage said staple-forming and staple-driving bars to move same forward to form and drive a staple, a restoring spring tending to retain said bars in engagement with said cam, and retracting means mounted on said revolute shaft adapted to return one of said bars after the staple-forming and driving operation.

25 3. A stapling machine comprising staple-forming mechanism, including a staple-forming bar, a staple-driving bar cooperating with said staple-forming bar, a revolute shaft, a cam mounted on said revolute shaft adapted to engage said bars to move same forward to form and drive a staple, one of said bars having a cam face, and retracting means comprising a spring tending to restore said bars, a rotary member mounted on said revolute main shaft and a projection extending from said rotary member, said projection being adapted to engage said inclined face to positively restore one of said bars.

40 4. A stapling machine comprising staple-forming mechanism including a staple-forming bar, a staple-driving bar cooperating with said staple-forming bar, said staple-forming bar being provided with a cam groove, a revolute shaft, a cam mounted on said revolute shaft adapted to engage said staple-forming and staple-driving bars to move same forward to form and drive a staple, retracting means comprising a disk mounted on said revolute shaft, and a projection extending from said disk, said projection being adapted to enter the cam groove in said staple-forming bar to return

said staple-forming bar to its rearward position and means whereby said staple-driving bar is moved rearwardly by said staple-forming bar.

45 5. A stapling machine comprising staple-forming mechanism including a staple-forming bar, a staple-driving bar cooperating with said staple-forming bar, said staple-forming bar being provided with a cam groove, a revolute main shaft, a cam mounted on said revolute main shaft adapted to engage said staple-forming and staple-driving bars to move same forward to form and drive a staple, retracting means comprising a rotary member mounted on said revolute main shaft, and a pair of projections extending from said rotary member, said projections being adapted to successively enter the cam groove in said staple-forming bar to return said staple-forming bar.

50 6. A stapling machine comprising staple-forming mechanism including a staple-forming bar, a staple-driving bar cooperating with said staple-forming bar, said staple-forming bar being provided with a cam groove, a revolute main shaft, a cam mounted on said revolute main shaft adapted to engage said staple-forming bar and said staple driving bar to move same forward to form and drive a staple, retracting means comprising a disk mounted on said revolute main shaft, a plate secured to said disk, a projection extending from said plate, said projection being adapted to enter the cam groove in said staple-forming bar to return said staple-forming bar to its rearward position.

55 7. A stapling machine comprising staple-forming mechanism including a staple-forming bar, a staple driving bar cooperating with said staple-forming bar, said staple-forming bar being provided with a cam groove, a revolute main shaft, a cam mounted on said revolute main shaft adapted to engage said staple forming bar and said staple driving bar to move same forward to form and drive a staple, retracting means comprising a rotary member on said revolute main shaft, said rotary member being provided with an aperture, a plate carried by said rotary member, a projection on said plate, said projection being adapted to extend through the aperture in said rotary member and to enter the cam groove in said staple-forming bar to return said staple-forming bar to its rearward position, and means whereby said staple-driving bar is moved rearwardly by said staple-forming bar.

60 8. A stapling machine comprising staple-forming mechanism including a staple-forming bar, a staple-driving bar slidably connected to said staple-forming bar, said staple-forming bar being provided with a

cam groove, a revolute main shaft, a cam mounted on said revolute main shaft adapted to engage said staple-forming bar and said staple-driving bar to move same forward to form and drive a staple, retracting means comprising a disk mounted on said revolute main shaft, said disk being provided with a pair of apertures, a plate located on said disk adjacent to said apertures, a pair of rollers mounted on said plate, said rollers being adapted to extend through the apertures in said disk and to successively enter the cam groove in said staple-forming bar to return said staple-forming bar and said staple-driving bar to their rearward positions, dowels secured to said plate and adapted to extend into said disk, and a screw whereby said plate is attached to said disk.

20. 9. A stapling machine comprising staple-forming mechanism including a staple-forming bar, a staple-driving bar cooperating with said staple-forming bar, driving means adapted to engage said staple-forming and said staple-driving bars whereby said staple-forming and said staple-driving bars are moved forward to form and drive a staple, retracting means comprising a rotary member adapted to return said staple-forming bar and a spring cooperating with said rotary member whereby said staple-forming bar is returned to its rearward position and means whereby said staple-driving bar is moved rearwardly by said staple-forming bar after the staple-forming and driving operation.

10. A stapling machine comprising staple-forming mechanism including a staple-forming bar, a staple-driving bar cooperating with said staple-forming bar, said staple-forming bar being provided with a cam groove, a revolute main shaft, a cam mounted on said main shaft adapted to engage said staple-forming bar and said staple-driving bar to move said bars forward to form and drive a staple, retracting means comprising a disk mounted on said revolute main shaft, said disk being provided with a projection adapted to enter the cam groove in said staple-forming bar, and an expansive coil spring adapted to exert a rearward pressure against said staple-forming bar, whereby said staple forming bar is returned to its rearward position and means whereby said staple-driving bar is moved rearwardly by said staple-forming bar after the staple-forming and driving operation.

11. A stapling machine comprising staple-forming mechanism including a staple-forming bar, a staple-driving bar slidably connected to said staple-forming bar, said staple-forming bar being provided with a cam groove, a revolute main shaft, a cam mounted on said main shaft adapted to engage said staple-forming and said staple-driving bars to move same forward to form and drive a staple, and retracting means comprising a disk mounted on said revolute main shaft, said disk being provided with a projection adapted to enter the cam groove in said staple-forming bar, a spring housing, an expansive coil within said spring housing, and a plunger against which said expansive coil spring bears, said plunger being adapted to bear against a portion of the staple-forming bar whereby said staple-forming bar is returned to its rearward position and means whereby said staple driving bar is moved rearwardly by said staple-forming bar after the staple-forming and driving operation.

12. A stapling machine comprising staple-forming mechanism including a staple-forming bar, a staple-driving bar slidably connected to said staple-forming bar, said staple-forming bar being provided with a cam groove, a revolute main shaft, a cam mounted on said main shaft and having cam faces adapted to engage said staple-forming bar and staple-driving bar to move said bars forward to form and drive a staple, retracting means comprising a disk mounted on said revolute main shaft and provided with a pair of apertures, a plate located on said disk adjacent to said apertures, said plate being provided with a pair of rollers extending through the apertures in said disk to successively enter said cam groove in said staple-forming bar, dowels secured to said plate and extending into said disk, a spring housing, an expansive coil spring within said spring housing, and a plunger against which said expansive coil spring bears, said plunger being adapted to bear against a portion of said staple-forming bar whereby said staple-forming bar is returned to its rearward position and means comprising a slot and pin connection between said staple-forming and said staple-driving bars whereby said staple driving bar is returned to its rearward position.

In testimony that I claim the foregoing I hereunto affix my signature.

GEORGE A. EDE.
